Attorney

UNITED STATES PATENT OFFICE.

CHESTER W. TULLAR, OF DETROIT, MICHIGAN.

ENVELOP.

1,369,503.

Specification of Letters Patent. Patented Feb. 22, 1921.

Application filed March 8, 1920. Serial No. 364,228.

To all whom it may concern:

Be it known that I, CHESTER W. TULLAR, citizen of the United States, residing at Detroit, county of Wayne, State of Michigan, have invented a certain new and useful Improvements in Envelops, and declare the following to be a full, clear, and exact description of the same, such as will enable others skilled in the art to which it pertains to make and use the same, reference being had to the accompanying drawings, which form a part of this specification.

My invention relates to envelops and more particularly to the class of envelops employed for mailing circulars, catalogues and the like in which the flap of the envelop is left unsealed to effect a saving in postal rates.

One object of my invention is to provide means adapted to protect the contents of the envelop against accidental discharge therefrom but which does not necessitate the "sealing" of the flap.

A further object of the invention is to provide for the protection of the contents of the envelop without adding, or materially adding to the cost of manufacture as envelops are ordinarily constructed.

With the foregoing and other objects in view which will appear as the description proceeds, the invention resides in the combination and arrangement of parts and in the details of construction hereinafter described and claimed, it being understood that changes may be made in the precise embodiment of the invention herein disclosed without departing from the spirit of the same.

In the accompanying drawings forming part of this specification:—

Figure 1 is a rear elevation of an envelop having a "side opening" embodying my invention.

Fig. 2 is a similar elevation of an envelop constructed with an "end opening."

Fig. 3 is a rear elevation of an "end opening" envelop employing a plural number of tongue engaging devices.

Fig. 4 is a rear elevation of an envelop in

which the walls "overlap" sufficiently to form a "reinforced" engaging device thereby providing for increased wear.

50

Fig. 5 is an enlarged fragmentary cross-sectional view on line 5—5 of Fig. 1.

Fig. 6 is a like cross-sectional view on line 6—6 of Fig. 4.

Fig. 7 is a view of a "blank" for a side opening envelop.

Fig. 8 is a view of a "blank" for the envelop shown in Fig. 4 of the drawings.

Referring now to the letters of reference placed upon the drawings:—

60

A, denotes an envelop, B, the usual side or end flap, slitted as at B' to receive an engaging tongue C, integral with the back wall of the envelop. If desired an envelop may be constructed with a plural number of engaging tongues C, as indicated in Fig. 3 of the drawings, thus preventing the loss of any relatively small articles that may be inclosed in the envelop.

65

To provide for increased use or wear of the engaging tongue C, the portions forming the back of the envelop may be constructed so as to overlap, as indicated in Figs. 4, 6, and 8 of the drawing.

70

Having indicated the several parts by reference letters, it will be seen that upon filling the envelop with the circular matter to be mailed, the sender "turns in" the flaps so as to overlap the contents of the envelop, and then inserts the engaging tongue C in the slit B' of the flap. The "mouth" of the envelop is thus secured against gaping, thereby protecting its contents from accidental discharge.

75

It will be noted that practically no additional expense is added by my invention to the cost of manufacturing envelops. The engaging tongue is constructed from that portion of the sheet usually cut away in forming the back wall of the envelop; while a saving is effected by eliminating the cost of clips or other engaging devices together with the loss of time required for installing these devices upon the envelops.

80

85

90

95

Having thus described my invention what I claim is:—

An envelop having a relatively narrow unsealed closure flap disposed loosely against the body of the envelop and provided with a slit, the slit in the flap being disposed adjacent one edge of the envelop body, and the rear wall of the envelop having a relatively short projecting ungummed tongue adapted 10 to extend through said slit and be wholly confined within the envelop and free of either

the closure flap or the body of the envelop, the contents of the envelop adapted to hold the tongue against the closure flap, thereby preventing displacement of the tongue. 15

In testimony whereof, I sign this specification in the presence of two witnesses.

CHESTER W. TULLAR.

Witnesses:

S. E. THOMAS,
JOHN CONSIDINE, Jr.
